UNITED STATES PATENT OFFICE.

FRANK WHEELER, OF MERIDEN, CONNECTICUT.

SYSTEM OF ELECTRICAL LOCOMOTION.

SPECIFICATION forming part of Letters Patent No. 431,095, dated July 1, 1890.

Application filed December 28, 1889. Serial No. 335,236. (No model.)

To all whom it may concern:

Be it known that I, FRANK WHEELER, of Meriden, in the county of New Haven and State of Connecticut, have invented new and useful Improvements in Systems of Electric Locomotion; and I do hereby declare the following to be a full, clear, and exact description of said invention, reference being had to the accompanying drawings, and to the letters of reference marked thereon, which form a part of this specification.

My invention relates to improvements in systems of electric locomotion in which a single car-track provided with turn-outs and an overhead trolley-track and conductor are employed, said track being of a kind to support a trolley traveling thereon. In such systems it is customary for two cars meeting at a turn-out to exchange trolleys, the trolley-track being single throughout its length—that is, unprovided with turn-outs. Such exchange of trolleys is objectionable for several reasons, among them being the necessary stoppage of one or both of the cars and the extinguishing of the lights in the cars at night during the disconnection of the depending conductors from the cars.

The object of my invention is to avoid these objections by rendering practical an arrangement of the trolley-track similar to the car-track, whereby each car may carry its trolley from end to end of the line without disconnection. These objects I attain by the construction and combination of parts in which my invention consists, as hereinafter described, and pointed out in the claims.

In the drawings, which accompany and form part of this specification, Figure 1 is a plan view of my improved switch, the ends of the main-line trolley-track x being shown at the left and the ends of the turn-out tracks x' x'' being shown at the right. Fig. 2 is a longitudinal section on line 2 2 of Fig. 1. Fig. 3 is a cross-section on line 3 3 of Fig. 1. Fig. 4 is a detail perspective of the top plate of the pivot-rod, showing the stop-lugs thereof. Fig. 5 is a diagram showing a turn-out and a switch at each end thereof. Fig. 6 is a perspective view of my improved clip, the parts being united. Fig. 7 is a perspective view of the clip, the parts being separated. Fig. 8 is

a cross-section on line 8 8 of Fig. 6, and Fig. 9 is a side elevation of a double clip.

The switch A is composed of the frame a a' , of which the portions a' are bars or rods connecting the end portions and the portion a^2 is a brace connecting the two rods a' at or near their middle. This brace a^2 is provided at a point in a straight line between the tracks x and x' with a circular plate b' , forming the under plate of the turn-table B. The center is bored out to allow the pivot-rod c of the switch-track C to pass through. The upper end of the pivot-rod is screw-threaded, and just below the screw-threaded portion the rod 55 is squared or otherwise suitably angular in cross-section to fit a similar-shaped opening in the upper plate b of the turn-table, a nut b^2 on the end of the pivot-rod holding it in position. The two plates b b' are annularly 60 grooved to receive the anti-friction balls b^3 .

To the lower end of the pivot-rod c is securely fastened the switch-track C, which in this form consists of a light board having thereon the two metallic ways c' , extending 65 from track x to track x' , as shown in full lines in Fig. 1, and cut away, as at c^2 , for lightness. Brace-rods c^3 extend from end to end of track C, passing over hooks c^4 , projecting one on each side of the rod c , the 70 track C, rods c^3 , and pivot-rod c thus forming a light but strong truss.

A spring b^4 , coiled around pivot-rod c , with its lower end secured thereto and the upper end secured to plate b' or to a pin b^5 , projecting downward therefrom, serves to keep the switch-track normally in the position shown by the full lines in Fig. 1, whereby the trolley D is free to pass from turn-out track x' to main track x .

The trolley D, (see Fig. 3,) having wheels d for running on the ways c' , is provided on one side with a bracket d' , having a vertical pin, on which is mounted the roller d^2 .

To the frame at a^3 is pivoted the guide E, 95 its long arm e extending toward the brace a^2 and its end being inside the path of travel of roller d^2 of the trolley, and the short arm e' being kept normally against a stop portion a^4 of the frame by means of spring e^2 , as 100 shown in full lines in Figs. 1 and 3. It will thus be seen that when a trolley is moving

- in the direction of the arrow z in Fig. 1 its roller d^2 will engage the outer edge of the long arm e of the guide, and as the trolley is farther drawn by the moving car in 5 said direction the trolley will be drawn to one side, and consequently the switch-track will be swung on its pivot-rod c to the position shown in dotted lines in Fig. 1, thus switching the trolley onto the right-hand 10 turn-out track x^2 , and as soon as the roller d^2 has passed the pivotal point a^3 of the guide and the trolley has passed onto track x^2 the switch-track is moved back to its normal position by the action of the spring b^4 , leaving 15 the switch in position to conduct a trolley from track x' to track x . When a car reaches the end of the line and is to return, the trolley is not removed from its track. Consequently the rollers d^2 of two trolleys, passing 20 each other on a turn-out, project in the same direction. Therefore, in order to allow the roller d^2 of a trolley moving from track x' to track x to pass the guide E , the said guide is pivoted at a^3 , as above described, whereby the 25 roller in so passing will simply push the guide slightly to one side, as indicated in dotted lines in Fig. 1, and after passing the guide will be returned to its normal position by spring e^2 .
- 30 On the brace a^2 , or on the under plate b' of the turn-table, are two stops f' , against which the lugs f of the upper plate b abut to limit the extent of movement of the switch; but since the guide E will cause a trolley to 35 swing the switch but a certain distance I may dispense with the lug and stop for limiting the motion in that direction. The switch-frame shown is angular in outline; but it is obvious that it may be circular or otherwise 40 suitably shaped.
- Other changes in details of construction may be made without departing from the spirit of my invention. For instance, the relative proportions of some of the parts may 45 be altered, or the switch-track and its ways c' need not be perfectly straight, it being only necessary that the ends of the ways shall be in line with the ends of tracks x , x' , and x^2 when in their operative positions; also, to stop 50 or limit the motion of the switch-track at each of its extremes I may bevel or shoulder the meeting ends of one of the ways c' and one of the tracks x and x^2 , as shown at x^3 .
- It will be understood that without materially altering the construction of the switch 55 it may serve for a diamond crossing by securing the end of a fourth track in position to meet the left-hand end of the switch when it is in the position indicated by dotted lines in 60 Fig. 1.
- By means of a pivoted switch-track, as described, a crossing at any angle can be arranged, the ends of the trolley-tracks proper being secured in the desired direction and at the 65 proper distance from the pivot of the switch-track; but in such construction it will be necessary, of course, to operate the switch-track positively by external means, as by two cords connected to it and passing over pulleys such as shown in my application filed December 70 23, 1889, Serial No. 334,702.
- An advantage of a turn-table switch—that is, one in which both ends of the switch-track move simultaneously—over one in which the switch track or tracks are pivoted to the ends 75 of the main track is, that not only can a crossing be made of it, but there can be no short-circuiting through the switch-tracks, for the reason that in switching, when one end of a switch-track passes a live wire its other end 80 is out of position to complete a circuit.
- In Figs. 6, 7, and 8 I illustrate in several enlarged views the clip for holding the ends of the track-wires where connected to the switch-frame, as at G in Fig. 1. I not only 85 propose to use this clip at all points where track-wires meet a switch-frame, but also at all points where the end of a track-wire is to be secured. The clip consists of a vertical plate g , having a horizontal portion g' provided with holes for receiving the screws which attach it to a hanger or other desired support. Diagonally across the face of plate g is a recess g^2 , one side of which is concaved or grooved, as at g^3 , meeting the concavity or 95 groove g^4 on the top of the plate. The track-wire x is bent, as shown, to fit the two concavities, and the end of the wire is bent underneath, as shown at g^5 . After the wire is fitted to its place a key g^6 is slipped into the 100 recess and secured there by means of a screw passing through a hole of the key into plate g or by other suitable means. When the parts are so secured, it will be impossible to remove the wire, except by removing key g^6 105 or by breaking the wire. The tops of plate g and key g^6 are rounded to allow a trolley to run smoothly thereover.
- When it is desired to join two wire ends at some intermediate point along the line, I propose to utilize a double clip, such as shown at G' in Fig. 9, the clip being prevented from 110 turning by being secured to a hanger. In this clip G' , I make the recess with two concave upwardly-diverging sides g^7 and make 115 the key wedge-shaped, as shown at g^8 .
- It is obvious that I may vary the angle of the recess, and that the side thereof opposite the concaved side may be vertical, the key being correspondingly shaped; but the concaved side should be at such an angle to the top as to avoid a sharp bend in the wire at the point g^8 , where the greatest liability would exist of breaking.
- To prevent short-circuiting through the 120 brace-rods c^3 and the metallic ways c' , I may interpose insulating material at c^5 .
- Having now described my invention, what I claim, and desire to secure by Letters Patent, is—

1. In a trolley-switch, the combination, with a swinging switch-track, of a guide for engaging a portion of a trolley, said guide being pivoted to the frame of the switch, substantially as described.
2. In a trolley-switch, the combination, with a swinging switch-track, of a spring for moving it in one direction, a stop for limiting its movement in that direction, a guide pivoted to the frame of the switch, a stop for said guide, and a spring for normally holding the guide in engagement with said stop, substantially as described.
3. A trolley having a bracket secured thereto and a roller mounted on said bracket, in combination with a switch-track frame having a guide pivoted thereto, substantially as described.
4. In combination with a pivoted or swinging switch-track, a guide located between the center of motion of the trolley-switch track and the end of an adjoining track, and a trolley having a projection adapted to engage said guide, substantially as described.
5. A switch for systems of electric locomotion, consisting of a frame and a switch-track pivoted in said frame and extending in two directions from the pivot, substantially as described.
6. A switch consisting of a frame and a switch-track pivoted at or near the center of the frame, in combination with a plurality of trolley-tracks terminating at said frame, substantially as described.
7. A clip for securing a trolley-track wire having a vertical plate, said plate being recessed, one side of said recess being inclined, and a key for holding the wire against said inclined side, substantially as described.
8. A clip for securing a trolley-track wire, consisting of a vertical plate having a recess, one side of which is inclined and grooved, and the top of the plate being grooved from the recess to one end and convex or rounded from the recess to the other end, and a key having one side grooved, and means for securing the key in position, substantially as described.

In testimony whereof I affix my signature in presence of two subscribing witnesses.

FRANK WHEELER.
